(57) **CLAIM**

The ornamental design for a dish rack, as shown and described.

DESCRIPTION

FIG. 1 is a perspective view of a dish rack showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of an indicated portion of FIG. 1; and,

FIG. 10 is an enlarged view of an indicated portion of FIG. 3.

The broken lines in FIGS. 1-10 depict portions of the dish rack that form no part of the claimed design. The dot-dash broken lines in FIGS. 1-4, 7 and 9-10 represent unclaimed boundary lines and form no part of the claimed design. The dot-dot-dash broken lines in FIGS. 1, 3 and 9-10 are for the purpose of annotating the enlarged views and form no part of the claimed design.

1 Claim, 10 Drawing Sheets
